VALVE KEEPER INSERTER

Harry W. Kulp and Martin C. Dellinger, Lancaster, Pa., assignors to K-D Manufacturing Company, Lancaster, Pa., a corporation of Pennsylvania

Application May 4, 1932, Serial No. 609,308
Renewed September 12, 1933

6 Claims. (Cl. 81—5.1)

This application is for improvements on our invention set forth in our Patent No. 1,850,268, granted March 22, 1932, for Positioning tools, and is of the same general type of easily loaded tool set forth in our Patent No. 1,896,001 granted Jan. 31, 1933 for Valve keeper inserter.

This present invention relates to tools primarily intended for use in inserting and properly positioning the removable locking means cooperating with the lower end portions respectively, of the respective valve stems of an internal combustion engine to limit the downward movement of the respective spring retainers or cups or washers, in connection with the operations necessary to the grinding or replacement of poppet valves in internal combustion engines, particularly internal combustion engines as mounted in automobiles and as confined and obstructed by the related parts, such as the generator, distributor, carburetor, steering rod, chassis frame and other parts of the automobile.

In using devices made in accordance with the embodiment illustrated in our above identified patent it has been found in servicing some engines wherein the valve stems B have a greatly reduced portion P with correspondingly small opening between the opposed faces of the cooperating pair of keeper members E, that sometimes the mechanic will let the jaws of the tool close against the valve stem B out of registry with the reduced portion P with the result that the keeper members E and the forward portions of arms 9 cannot move further inward toward each other, but the jaws 6 under the pressure of spring 12 move to closed position, thus causing the stops or flanges 8 to move away from the keeper element E, which are thus no longer gripped between the respective arms 9 and their respective pairs of stops or flanges 8.

The primary objects of the present invention are to provide independent spring means for actuating the gripping arms in the respective jaws and independent spring means for forcing the jaws toward each other to closed position, the applied force of the actuating springs of the gripping arms being at least as great, and preferably in excess of, the applied force of the spring for closing the jaws, to overcome the objection above referred to; to provide easy means for manipulating the keeper gripping arms 9 to facilitate the easy and quick insertion of the keepers in the respective jaws of the tool preliminary to their application to a valve stem, and to simplify the construction.

In this application we show and describe only

the preferred embodiment of our invention simply by way of illustration of the practice thereof, as by law required. However, we are well aware that our invention is capable of other and different embodiments and that the various details thereof may be modified in a number of different ways, all without departing from our said invention; therefore, the drawing and description herein are to be considered as merely illustrative and not as exclusive.

In the accompanying drawing:

Figure 1 represents a perspective view of a tool embodying our invention, with the split cone keeper members held therein, as used in applying said keepers to a valve stem of an engine, the spring and retainer on said stem being shown raised by a valve-spring lifter preparatory to the application of the keepers;

Figure 2, a top plan view of the tool embodying our invention, with keeper elements E gripped between the respective pairs of stops or flanges and the cooperating gripping arms 9;

Figure 3, a fragmentary detail bottom plan view;

Figure 4, a sectional view on the line 4—4 of Fig. 2, looking in the direction of the arrows;

Figure 5, a section on line 5—5 of Fig. 2, looking in the direction of the arrows; and

Figure 6, a detail perspective view of one of the gripping arms 9 with its integral lever arm 14 and thumb piece 15, its actuating spring 12, and the handle movement limit stop 4.

All views of the drawing are made to actual full-size scale from an actual commercial physical embodiment of the tool.

Referring now in detail to the drawing, A designates the engine generally, B, the valve-stems of the usual poppet-valves (not shown) thereof; C, the usual valve-springs; D, the valve-spring retainers, cups or washers; E, the split cone keepers or locking means normally received in the reduced portion F of the valve-stems B with their cone faces presented upwardly and resting on the lower annular shoulder G of the valve-stem and normally so held by the cooperating inner lower conical face of the retainers or cups or washers D; H, the push rod spider; J, the push rods; K, the adjustable push rod heads, and L, the lock nuts for the latter.

The parts specifically immediately above referred to are old and well known and are merely briefly described as above to aid in giving a clearer understanding of the present invention.

M designates generally a valve-spring lifter with which the present invention is preferably

used, and said valve-spring lifter may be constructed as illustrated in accordance with our Patent No. 1,879,330, granted Sept. 27, 1932 for Valve spring lifter.

5 In the embodiment illustrated two preferably light thin sheet metal members of generally U-shape in cross section having their inner channel faces presented toward each other are provided with oppositely presented lugs 1 and 2, the lugs 2 of the one member fitting between the lugs 1 of the other, and a pivot pin 3 passing through said lapped lugs 1 and 2 and between the engaging arcuate fulcrum faces 11 and through registering perforations in the ends of the stop member 4, and having its ends upset in usual known manner, serves to pivotally connect the two members.

20 Each of the body members so pivotally connected preferably consists of a handle or lever portion 5 extending rearward from the pivot 3 and an operative jaw 6 extending forward from said pivot 3.

25 Each jaw has its inner edge portion cut out preferably in the form of a semi-circle or approximately of that shape, as at 7, adjacent its forward end, the cuts-outs or notches of the respective jaws registering, when the jaws are closed to together define a substantially circular or preferably substantially circular opening to preferably freely accommodate a valve-stem between them when closed, said opening so defined preferably being of a diameter appreciably in excess of the diameter of the cylindrical portion of the valve-stem B, so that as the jaws are 30 forced downward by the usual spring retainer D in stripping the keepers E from the tool, the tool will not be caught between the upper face of shoulder G of the valve-stem B and the lower face of one or both of the keeper members E.

40 The opposed inner edges of the jaws 6 will preferably be formed with preferably continuous flanges 8 from said notches 7 at diametrically opposite points of the opening defined by the jaws 6 when closed, said flanges extending 45 lengthwise of the jaws 6. The function of these flanges 8 is to engage and act as stops for the straight radial faces of the corresponding keeper members or elements E as the latter are pressed against said stops by the corresponding keeper gripping arms 9.

50 The gripping arms 9 are formed preferably integrally with their respective operating or lever arms 14, said arms merging with each other at about the point of the arcuate fulcrum face 11 formed in the edge of said composite arm member. The rear end of arm 14 is bent at a sharp angle and in mounted position projects through a cooperating slot in the web 10 in its corresponding arm 5 to provide a laterally extending thumb or finger piece 15 to be engaged by the thumb or 55 finger of the mechanic. The inner edge face of the front end portion of each arm 9 is cut out in an elongated V-shape so as to engage and properly position the keeper element or cone member E, and the edge of said notch is downwardly and outwardly inclined to be parallel to, and to engage over a wide area of, the opposed outer peripheral face of a keeper element E gripped between said arm 9 and the cooperating 60 stops or flanges 8 of the corresponding jaws 6.

65 An individual actuating spring 12 mounted in its corresponding jaw 6 is provided to press its corresponding gripping arm 9 toward the co-operating pair of stops or flanges 8 of said jaw 6. 70 A separate coil pressure spring 17 independent

of the springs 12 is interposed between the arms 5 and has its end portions abruptly bent and received in cooperating sockets or perforations in the webs 10 of the arms and, in the embodiment illustrated, has the sole function of forcing the arms 5 away from each other about the pivot pin 3 to force the jaws 6 toward each other.

5 75 Each spring 12 is of leaf spring construction having a long front arm extending laterally outwardly and rearwardly to form a relatively sharp angle or hump 16 at the point where it merges with the laterally outwardly and forwardly extending shorter arm. In operative assembled relation each spring 12 has its hump 16 received in the socket or slot 13 in the web 10 of its corresponding jaw 6 and engages with its forward end the laterally outer face of its corresponding gripping arm 9 to force the same about the pivot 3 toward its corresponding pair of stops 8, and has its rear end in engagement with the laterally outer face of said gripping arm 9 adjacent the pivot 3 to maintain the said spring 12 in proper operative position with its hump 16 in its cooperating socket or slot 13 and to maintain said spring 12 under proper compression as a 20 25 whole.

30 35 Each spring 12 is of such size and strength and has its point of application of pressure to the forward end of its cooperating arm 9 so related to the fulcrum point or pivotal point of said arm 9 that said spring 12 applies a greater shove, thrust or pressure against its said cooperating gripping arm 9 than the power exerted by the spring 17 to force the jaws 6 toward each other. Consequently, in case the keeper members E should engage against the larger cylindrical portions of a stem P, the greater pressure exerted by the springs 12 will prevent relative movement between the gripping arms 9 and their respective jaws 6, so that the jaws 6 will not under such 40 45 conditions be moved toward each other independently of their respective gripping arms 9 and consequently under the condition mentioned the keeper elements E will not be released.

50 55 To assemble the tool, the respective elements comprised of its arm 9 and its cooperating lever 14 and thumb piece 15 are arranged lengthwise in each sheet metal member, with the thumb piece 15 extending through the cooperating slot in the web 10 of said member, the respective springs 12 are mounted in the respective jaws 6, next the two thin sheet metal members are fitted together with the lugs 2 of the one fitted between the lugs 1 of the other. The U-shape stop member 4 having end portions lying outside of the lugs 1 is then applied and, finally, the pivot pin 3 is inserted and has its ends riveted over or upset. Thus, the one pivot pin 3 serves to tie all parts of the tool together in operative relation.

60 65 The bottom or loop of the U-shape stop member 4 extends from side to side between the opposed channel faces of the handle or lever portions 5 and so positively prevents the movement of said handles 5 toward each other beyond a predetermined point.

70 75 Preferably the forward outer portions of the respective jaws 6 will be folded over against the lower faces of said jaws to reinforce said jaws at this point and to obtain a narrow forward end of the tool for greater ease of access while bracing said jaws 6 at this point, so obtaining the smaller end of the tool without sacrificing strength of the individual front end portions of the respective jaws 6, and without requiring the use of a heavier weight or gage of sheet metal 80 85 90 95

to maintain the desired strength of the jaws at such points.

In use, with the parts assembled as above described, to load the tool with the keeper elements 5 or cone members E, it suffices to press first one thumb piece 15 inward so as to cause the corresponding arm 9 to move away from the corresponding pair of stops 8 sufficiently to permit the insertion of a keeper element E between the 10 opposed face of the V-shape notch of the arm 9 and the opposed faces of the cooperating pair of stops 8 of one of the jaws 6, as illustrated in Fig. 2, the same operation being repeated to load the other jaw 6, when the parts will be in the position 15 illustrated in Figs. 1 and 2. Thereafter the handles 5 will be pressed toward each other to spread the jaws 6 so as to receive the valve-stem B in the notches 7 between the respective jaws 6 incident to the application of the gripped pair of 20 keeper elements E in obvious and well known manner.

We claim:

1. A valve-stem locking-element inserting tool comprising a pair of channel form sheet metal members, each comprising a pair of vertically registering laterally presented perforated lugs, a handle portion extending to the rear of said lugs and a jaw portion extending forwardly of said lugs, said jaw portions having their opposed inner edges adjacent their front ends notched out in registry to cooperate in defining between them, in closed position, an opening to receive the valve-stem, the web portions of each said member being formed with a slot in advance of said lugs and with a rear slot to the rear of said lugs; stop means carried by said jaw portions respectively to be engaged by the respective radial faces of the respective locking elements; and a pivot pin extending through the registering perforations of said lugs and having its ends upset to pivotally secure said members together, in combination with a pair of elements respectively disposed in said members, each said element comprising a gripping arm, a lever arm, an arcuate inwardly presented fulcrum face disposed at the point of emergence of said arms, and a finger piece extending from the rear portion of said lever arm through said rear slot in the web of its respective member, and said gripping 50 arm being formed with a V-shaped centering notch presented toward and in transverse registry with the notch in its cooperating jaw portion of said member, leaf springs of generally semi-elliptical shape disposed in the respective 55 jaw portions, each said leaf spring being formed with a hump portion received in the forward slot of the web portion of its respective jaw portion and bearing with its respective end portions against the opposed outer face of its cooperating gripping jaw portion by its rear end adjacent the pivot and by its forward end adjacent the forward end of said gripping arms and being at all times maintained under compression whereby it is maintained in assembled relation, and independent spring means for urging said jaw portions toward each other, said leaf springs being so related to said gripping arms and of such strength as to apply greater force to the forward portions of their respective gripping arms than is applied by said spring means to urge said jaw portions toward each other, and said pivot pin being engaged by the fulcrum face of, and serving as the fulcrum point for, said elements.

2. A valve-stem locking element inserting tool comprising a pair of channel form sheet metal

members, each comprising a pair of vertically registering laterally presented perforated lugs, a handle portion extending to the rear of said lugs and a jaw portion extending forwardly of said lugs, said jaw portions having their opposed inner edges adjacent their front ends notched out in registry to cooperate in defining between them, in closed position, an opening to receive the valve-stem, the web portions of each said member being formed with a slot in advance of said lugs and with a rear slot to the rear of said lugs; stop means carried by said jaw portions respectively to be engaged by the respective radial faces of the respective locking elements and a pivot pin extending through the registering perforations of said lugs and having its ends upset to pivotally secure said members together, in combination with a pair of elements respectively disposed in said members, each said element comprising a gripping arm and a lever arm, leaf springs of generally semi-elliptical shape disposed in the respective jaw portions, each said leaf spring being formed with a hump portion received in the forward slot of the web portion of its respective jaw portion and bearing with its respective end portions against the opposed outer face of its cooperating gripping jaw portion by its rear end adjacent the pivot and by its forward end adjacent the forward end of said gripping arms and being at all times maintained under compression whereby it is maintained in assembled relation, and independent spring means for urging said jaw portions toward each other, and said pivot pin being engaged by, and serving as the fulcrum point for, said elements.

3. A valve-stem locking-element inserting tool comprising a pair of pivotally connected members, each comprising a rearwardly extending handle portion and a forwardly extending jaw portion, said jaw portions having their opposed inner edges adjacent their front ends notched out in registry to cooperate in defining between them, in closed position, an opening to receive the valve-stem; stop means carried by said jaw portions respectively to be engaged by the respective radial faces of the respective locking elements and a pivot pin for pivotally connecting said members together, in combination with a pair of elements respectively mounted on said members, each said element comprising a gripping arm, and a lever arm, individual springs acting to force said gripping arms toward their stop means, and independent spring means for urging said jaw portions toward each other, said individual springs being so related to said gripping arms and of such strength as to apply greater force to the forward portions of their respective gripping arms than is applied by said spring means to urge said jaw portions toward each other, and said pivot pin being engaged by, and serving as the fulcrum point for, said elements.

4. A valve-stem locking element inserting tool comprising a pair of lever members connected with each other and adapted to swing toward and from each other in a single plane, said lever members having their opposed inner edges adjacent their front ends notched out in registry to cooperate in defining between them, in closed position, an opening to receive the valve-stem, and stop means carried by said lever members respectively adjacent the respective notches to be engaged by the respective radial faces of the respective locking elements, in combination with a pair of elements respectively swingably mounted on said members, each said element

comprising a gripping arm and a lever arm, independent springs respectively acting to force the respective gripping arm portions of said elements toward their cooperating stop means and distinct independent spring means acting to force said lever members toward each other, said latter spring means exerting less pressure to force said lever members toward each other than the pressure exerted by said independent springs upon the respective gripping arm portions of said elements.

5. A valve tool comprising a pair of levers, means connecting said levers for movement relative to each other, a pair of elements respectively 10 swingably mounted with relation to said levers, each said element comprising a gripping arm and a lever arm, and stops associated with each lever and adapted to cooperate with their corresponding gripping arm in holding a half of a split sleeve valve keeper, in combination with 15 resilient means urging said gripping arms toward their respective stops, and independent yielding means urging said levers toward each other, said resilient means being so related to said

elements and of such strength as to exert greater power to urge said gripping arms toward their respective cooperating stops than is exerted by said yielding means to urge said levers toward each other.

6. A valve tool comprising a pair of levers, means connecting said levers for movement relative to each other, a pair of elements respectively swingably mounted with relation to said levers, each said element comprising a gripping arm and a lever arm, and stops associated with each lever and adapted to cooperate with their corresponding gripping arm in holding a half of a split sleeve valve keeper, in combination with resilient means urging said gripping arms toward their respective stops, and yielding means urging said levers toward each other, said resilient means exerting greater power to urge said gripping arms toward their respective cooperating stops than is exerted by said yielding means to urge said levers toward each other.
